UNITED STATES PATENT OFFICE.

ENGELBERT WILHELM SCHMITZ AND JOHANNES WALLMANN, OF BERLIN,
GERMANY.

CAR-COUPING.

SPECIFICATION forming part of Letters Patent No. 516,123, dated March 6, 1894.

Application filed February 20, 1893. Serial No. 463,140. (No model.)

To all whom it may concern:

Be it known that we, ENGELBERT WILHELM SCHMITZ, of Annenstrasse 48, and JOHANNES WALLMANN, of Oranienstrasse, 173, Berlin,

5 in the Empire of Germany, have invented a new and useful Improvement in Self-Acting Couplings Disengaging from the Side for Railway-Carriages; and we do hereby declare that the following is a full, clear, and exact

10 description of the invention.

Figure 1 is a face view of the main-part A. Fig. 2 is a face view of the main-part B. Fig. 3 is a face view of the engaged coupling. Fig. 4 is a view of the inclined plane e.

15 While the many new railway-couplings are highly complicated and therefore very expensive the coupling described hereinafter is so simple as to be easily applied to any railway-carriage whatever.

20 It consists of two main-parts A and B, which are fixed alternately to the front-walls of the carriages. Part A has a piece a to which piece b turning round l is fixed. This piece b now carries the two flanges d d and in front 25 the inclined plane e with flue cheeks f f. Around g turns lever i with weight k and binding-piece h. Part B has a piece n to which piece p is fixed turning around m. This piece carries parts q, binding-piece r and pressing-piece s. The carriages being advanced toward one another, parts q and r will slide on the inclined plane e between the flanges d d and will then press lever i upward passing through below it until it is thrown back by

piece s. The lever thus pulling back, piece 35 h will come to lie on r and the coupling is engaged; the greater the force of drawing asunder, the tighter block r will press between h and b.

In order to disengage the coupling one need 40 only reverse the lever i from the side of the carriage which can be easily done since the fulerum is at the beginning of piece h. In order to compensate the difference of height between charged carriages and empty ones, 45 the springs c and o have been contrived which will yield and thus bring about a correct sliding in of the coupling-parts A and B.

Having thus described our invention, what we do claim as new, and desire to secure by 50 Letters Patent, is—

1. In a car coupling, the part B provided with the block r in combination with the part A having the plane b, and the flanges d, d, in which is pivoted weighted lever i having 55 thereon the binding piece h, all substantially as described.

2. In a car coupling the hinged part B having parts q, r and s, in combination with the hinged part A, having the incline e and cheeks 50 f f, and pivoted lever i and the springs c and o, all substantially as described.

ENGELBERT WILHELM SCHMITZ.
JOHANNES WALLMANN.
